UNITED STATES PATENT OFFICE

117,778

DESIGN FOR A COMBINATION BATHROOM DRESSER CABINET OR SIMILAR ARTICLE

Charles S. Amis, Washington, D. C.

Application August 31, 1939, Serial No. 86,991

Term of patent 7 years

To all whom it may concern:

Be it known that I, Charles S. Amis, a citizen of the United States of America, residing at Washington, in the District of Columbia, have invented a new, original, and ornamental Design for a Combination Bathroom Dresser Cabinet or Similar Article, of which the following is a specification, reference being had to the accompanying drawing, forming a part thereof, wherein:

Figure 1 is a perspective view of a combination bathroom dresser cabinet or similar article, showing my new design.

I claim:

The ornamental design for a combination bathroom dresser cabinet or similar article, as shown.

CHARLES S. AMIS.
